UNITED STATES PATENT OFFICE.

WILLIAM CHARLES YATES, OF LEMOORE, CALIFORNIA.

SURGICAL APPLIANCE.

No. 894,929.

Specification of Letters Patent.

Patented Aug. 4, 1908.

Application filed August 2, 1905. Serial No. 272,418.

To all whom it may concern:

Be it known that I, WILLIAM CHARLES YATES, a citizen of the United States, residing at Lemoore, in the county of Kings 5 and State of California, have invented a new and useful Surgical Appliance, of which the following is a specification.

This invention relates to surgical appliances.

10. The object of the invention is in a certain, cleanly and simple manner, by external application, and without soiling the clothing of the patient to cure private diseases.

With the above and other objects in view, 15 as will appear as the nature of the invention is better understood, the same consists in the novel construction of a device for treating private diseases, as will hereinafter be fully described and claimed.

20. In the accompanying drawings forming a part of this specification, and in which like characters of reference indicate corresponding parts, the figure is a view in perspective of the appliance.

25. The appliance comprises a gauze bag 1, larger at its closed than at its open end, and having one side cut away diagonally of its length from the open end to a point removed from the closed end, forming thereby a hood 2 at the latter end, the edges of the cutaway 30 portions being hemmed to provide a marginal pocket 3 in which is arranged a draw string 4 to hold the device properly positioned on the part to be treated.

In use, a hood is slipped over the glans 35 penis and the cord tied back of it, thereby holding the hood in situ, the prepuce is then drawn over the glans penis and the hood is saturated with a suitable medicament.

Having thus described the invention, what 40 is claimed is:—

A surgical appliance comprising a gauze bag, larger at its closed than at its open end, and having one side cut away diagonally of 45 its length from the open end to a point removed from the closed end forming thereby a hood at the latter end, the edges of the cutaway portions being hemmed to provide a marginal pocket, and a draw string arranged in the pocket. 50

In testimony that I claim the foregoing as my own, I have hereto affixed my signature in the presence of two witnesses.

WILLIAM CHARLES YATES.
